UNITED STATES PATENT OFFICE

LAWRENCE C. SMITH, OF DETROIT, MICHIGAN

FLOAT VALVE

Application filed December 12, 1927. Serial No. 239,587.

This invention relates to refrigerating apparatus and refers more particularly to the float valves thereof.

The invention has as one of its objects to provide a float valve of the above type distinguished by its simplicity of construction and operation which not only enhances its value both mechanically and commercially but provides a design of a strong and durable nature.

Float valves as now commercially produced are provided with a float chamber having a closure formed with inlet and outlet passages through which the refrigerating medium may be supplied to and removed from the chamber. The inlet passage for the refrigerating medium being controlled by a suitable valve member which engages a valve seat formed integral with the closure member. This latter arrangement is objectionable not only due to the time and labor required to accurately form the valve seat in the closure, but also owing to the fact that when the valve seat becomes worn or inaccurate, it is necessary to replace the entire closure.

It is therefore one of the primary objects of this invention to provide a detachable valve arrangement for controlling the inlet passage for the refrigerator wherein the valve seat may be readily removed without detaching the closure.

Other advantages and novel features of construction which contribute materially to the mechanical efficiency of the apparatus also add materially to its commercial value and acceptability together with the structural features of the invention will be made more apparent as this description proceeds especially when considered in connection with the accompanying drawing wherein

Figure 1 is a detail sectional view through a float chamber embodying my invention, and

Figure 2 is a front elevation thereof.

Referring now to the drawing, it will be noted that the numeral 10 designates a float chamber which may be attached to any suitable support such as the top of a brine tank (not shown) of a refrigerating apparatus.

The float chamber may be any shape desired and may be constructed of any suitable

material and is provided with an open end 11 closed by a cap 12 detachably secured to the chamber by means of the bolts 13. This cap is preferably a casting and is provided with the inlet and outlet passages 14 and 15 respectively through which the refrigerating medium may be supplied to and removed from the chamber when the cap is attached thereto. The outlet passage 15 is preferably formed in the upper portion of the cap and is provided with a funnel-shaped member 16, the mouth 17 of which is positioned a slight distance above the normal level of the refrigerating medium. The funnel is preferably formed of sheet metal and is secured to the mouth of the passage 15 in any suitable manner such as for example as by welding. The outer end of the passage 15 may be connected to a suitable conduit (not shown) for conveying refrigerant to the usual expansion coils 70 within the brine tank.

The inlet passage 14 is positioned below the normal level of the refrigerant and is provided with a threaded opening 18 for receiving the inlet valve assembly 19. As shown 75 the valve assembly comprises a stud 20 provided with a longitudinally extending bore 21 terminating in an enlarged bore 22 forming an annular shoulder 23 upon which a ball 24, arranged within the enlarged bore 22 is 80 adapted to seat. The enlarged bore 22 is further provided with a series of outlet ports 24' for the flow of refrigerant into the chamber 10. The outer end of the stud is provided with a slot or groove 25 for engagement by a 85 suitable tool so that the stud and consequently the inlet valve assembly may be readily removed when desired.

For operating the valve 24, I provide a float 26 having a relatively long arm 27 pivotally mounted as at 27' on a lug 28 projecting inwardly from the cap 12 substantially below the mouth 17 of the funnel shaped member 16. Journaled upon a pin 29 secured to the depending projection 29' formed on the outer end of the arm 27 is a member 30, which as shown projects downwardly from the arm 27 between the furcations 31 formed on the inwardly extending projection 32 of the cap 100 and engages the ball 24 for normally holding

the same seated upon the annular shoulder 23. As will further be noted from Figure 1 of the drawing the member 30 is fulcrumed intermediate the ends thereof upon a pin 33 secured to the furcations 31. Thus from the foregoing, it will be readily apparent that the valve 24 is operated by the member 20 which in turn is operated by the float, and the movement of the latter will be controlled by the level of the refrigerating medium.

Referring now to the operation of the apparatus, it will be noted that as gas is generated in the float chamber 10 and passed out through the outlet passage 15, the level of the 15 level of the refrigerating medium in the chamber 10 together with the float 26 is lowered. The device is so proportioned and designed that when the refrigerating medium in the float chamber reaches a certain predetermined level the ball 24 will be permitted to recede from the valve seat 23 allowing the refrigerating medium in the inlet passage 14 to enter the chamber. Referring more in detail to the mechanism for actuating the valve 20, it will be noted that when the level of the 25 refrigerating medium together with the float 26 is lowered in the chamber 10 the depending projection 29' together with the pivot 29 is swung downwardly about the pivot 27. As 30 the pivot 29 approaches the fulcrum 33 the outward pressure exerted upon the ball 24 by the member 30 to hold the ball against its seat is relieved and the member 30 is capable of a slight rocking movement about the pivot 35 29. With the parts in this position the refrigerating medium contained in the passage 14 forces the ball 24 and member 30 inwardly and flows into the chamber to replenish the supply thereof. As the level of the refrigerating medium in the chamber 10 rises the float 26 also rises and during this upward movement of the float 26 the pivot 29 moves inwardly or away from the fixed fulcrum 33 and accordingly forces the free end of the member 30 outwardly about the fulcrum 33 40 and into engagement with the ball 24 to move the same into engagement with its seat. The float 26 is so calibrated as to accurately control the level of the refrigerating medium 45 within the chamber irrespective of the amount of oil floating upon the top thereof.

From the foregoing it will be apparent that I have provided an improved float valve distinguished by its simplicity of construction and facility with which repairs may be made when required.

What I claim as my invention is:

1. A float chamber for refrigerating apparatus having inlet and outlet passages therein for a refrigerating medium and a detachable valve assembly comprising a valve seat and valve threadedly engaging one of said passages for controlling the flow of refrigerant therethrough, said valve assembly

being adapted to be removed from a point exteriorly of the chamber.

2. A float chamber for refrigerating apparatus having inlet and outlet passages therein for a refrigerating medium, a member threadedly engaging one of said passages having a longitudinally extending bore therein communicating with the interior of the chamber, and a valve arranged within said member for controlling the flow of refrigerating medium therethrough, said member and valve being removable from a point exteriorly of the chamber.

3. A float chamber for refrigerating apparatus having inlet and outlet passages therein for a refrigerating medium, a member threadedly engaging one of said passages having a longitudinally extending bore therethrough terminating in an annular valve seat and a valve member arranged within said bore and engageable with said seat for controlling the flow of refrigerant through said bore, said valve member and member aforesaid being readily removable from a point exteriorly of the chamber.

4. A float chamber for refrigerating apparatus having inlet and outlet passages therein for a refrigerating medium, a float positioned within said chamber and having an arm pivoted on the latter, a plug threadedly engaging one of the passages aforesaid and having a valve seat associated therewith, a valve member engageable with said seat, and means engageable with said valve member for actuating the same including a member pivotally mounted upon said arm adjacent the pivotal connection of the latter with the chamber and fulcrumed on the chamber.

5. A float chamber for refrigerating apparatus having inlet and outlet passages therein for the flow of a fluid, a float positioned within said chamber and having an arm pivoted on the latter, a valve for controlling the flow of refrigerant through one of said passages, and means engageable with the valve for actuating the same including a member pivoted at one end on said arm adjacent the pivotal connection of the latter with the chamber and fulcrumed intermediate the ends thereof on said chamber.

6. In a float chamber for refrigerating apparatus having an opening therein for a refrigerant, a readily detachable valve assembly comprising a valve seat and valve for controlling the flow of refrigerant through said opening, said valve assembly being adapted to be removed from a point exteriorly of the chamber.

In testimony whereof I affix my signature.

LAWRENCE C. SMITH.

DISCLAIMER

1,734,604.—*Lawrence C. Smith*, Detroit, Mich. FLOAT VALVE. Patent dated November 5, 1929. Disclaimer filed March 13, 1931, by the assignee, *Kelvinator Corporation*.

Hereby enters the following disclaimer, to wit:

A. Your petitioner disclaims from claims 1 and 6 of said Letters Patent all combinations of removable valve assemblies with refrigerant float chambers except combinations in which the valve assembly in its entirety is countersunk in the opening through which refrigerant is admitted to the chamber.

B. Your petitioner disclaims from claim 2 of said Letters Patent all removable valve assemblies except those in which the valve member is adapted to be unseated by the pressure of liquid in the conduit associated with the opening in the chamber within which the valve assembly is secured.

C. Your petitioner disclaims from claim 3 of said Letters Patent all removable valve assemblies except those in which the valve closing member is positioned between the valve seat and the inner extremity of the valve housing.
